REFRIGERATING APPARATUS

Lawrence A. Philipp, Detroit, Mich., assignor to
Nash-Kelvinator Corporation, Detroit, Mich.,
a corporation of Maryland

Original application April 25, 1939, Serial No.
269,997. Divided and this application December
6, 1940, Serial No. 368,847

1 Claim. (Cl. 62—103)

The present invention pertains to a refrigerating apparatus.

The present application is a division of my co-pending application Serial No. 269,997 filed April 25, 1939, for Refrigerating apparatus.

An object of the present invention is to provide an improved arrangement for disposing of the moisture from the evaporating element of a refrigerating system.

Another object of the present invention is to arrange for the drainage of the moisture from a collecting pan which is so arranged that the pan may be easily, quickly removed from, or retracted on, its support without necessitating attention to the drainage connection.

The invention itself, however, both as to its organization, and its method of operation together with additional objects and advantages thereof, will best be understood from the following description of specific embodiments when read in conjunction with the accompanying drawing, in which:

Fig. 1 is a central vertical longitudinal view in cross section of a refrigerator cabinet showing the invention applied;

Fig. 2 is a view taken along line 2—2 of Fig. 1;

Fig. 3 is a fragmentary vertical longitudinal view in cross section of a refrigerator illustrating a modified form of the invention for collecting and removing the melted ice defrosted from an evaporator;

Fig. 4 is a fragmentary view in cross section of a refrigerator illustrating a further modified form of the invention for collecting and removing the melted ice defrosted from an evaporator;

Fig. 5 is a fragmentary view in cross section of a refrigerator illustrating a modified form of the invention for vaporizing the water collected in the defrosting pan during the defrosting of an evaporator.

Referring to Fig. 1 in the drawing, a cabinet 10 is constructed of insulated side, top and bottom walls 12 to provide for a food storage compartment 16. The front wall 14 is provided with an opening 15 for access to the compartment 16 closed by a swingably mounted closure member 18. A second compartment 20 is provided in the cabinet 10 wherein is placed the compressor-condenser unit 22 of a refrigerating unit.

Secured to and suspended from the top wall within the food storage compartment 16 is an evaporator 24. Leading from the evaporator 24 for drawing heat laden refrigerant therefrom is a conduit 26 connected at its opposite end to the motor compressor unit 28. The compressor 28 is

connected by conduit 30 to the condenser 32. The passage of refrigerant through condenser 32 serves to liquefy the refrigerant to be conducted through a small diameter conduit 34 to the evaporator 24. The conduit 30 is formed intermediate the compressor unit 28 and condenser 32 into a spiral coil 36 in which is fitted a cup-shaped container or bucket 38. The coil 36 may be soldered, welded, or the like to the container 38 to form a thermal bond therebetween.

Preferably the system is operated so that little or no frost collects on the surface of the evaporator 24. The little frost that does collect is during the cycling of the compressor when there is a rapid withdrawal of gaseous refrigerant from the evaporator, but this frost quickly melts during the off-cycle of the compressor. The system may however be operated to collect and retain frost on the surfaces of the evaporator as is well understood in the art. In this case it is necessary to periodically defrost the evaporator. In order to catch this drip there is positioned beneath the evaporator a shallow pan 40. The pan 40 is carried on and serves also as a cover for the deep pan or food storage container 42 that is slidably supported on rails 44 secured on shelf 46. The shelf 46 is supported on brackets 48 provided on the side walls of the food storage compartment 16.

Secured in the rear wall of the pan 40 is a tube 50 so arranged as to permit drainage of the pan therethrough. The tube is bent to be directed downwardly to terminate above and to be in alignment with an open funnel shaped mouth 52 of a drain conduit 54 whose opposite end terminates within the open container 38. The arrangement of the tube 50 with drain conduit 54 allows drainage from pan 40 to container 38, also a ready retraction or withdrawal of the pan 40 from the compartment 16 may be had. The replacement of the pan 40 into position to catch the drip from the evaporator will align the tube 50 over the mouth 52 of conduit 54.

The condensate in the container or bucket 38 will be in heat exchange relation with the compressed refrigerant flowing through coil 36 toward the condenser 32. This relationship will tend to lower the temperature of the refrigerant in coil 36 while the vaporization of the condensate will be considerably increased so that the condensate will rapidly pass into the atmosphere in form of vapor. It will be noted that by this arrangement there is not only eliminated the necessity of manually removing the condensate from the pan, but also increases the efficiency of the condenser as it permits the re-

frigerant to enter the condenser at a lower temperature than normally would be the case.

In the modified form shown in Fig. 3 there is provided a deep pan 70 for the storage of foods such as meats and for catching the condensate that may drip from the evaporator 24 when it is being defrosted. A drain tube 72 is secured in the rear wall of pan 70 terminating above the funnel shaped opening 74 of drain conduit 76. Preferably the evaporator is operated to collect and maintain frost thereon when open type storage containers are used for the storage of meats and the like.

In the form shown in Fig. 4 the pan 70 is provided with a drain tube arranged as a U-shaped siphon 80 which also terminates over mouth 74 of the drain tube 76. The condensate collects in the pan 70 until a predetermined level is reached when it flows through the siphon tube 80 into conduit 76.

In Fig. 5 there is shown a modified form for the vaporization of the condensate by arranging an open trough 90 circumferentially on the shell of the motor-compressor unit 92. A drain conduit 94 terminates within the trough 90 emptying therein the condensate defrosted and collected from an evaporator. The heat created by the operation of the compressor and transmitted to, to be radiated by the shell will be absorbed

5 by the condensate or water, in the trough 90, increasing its vaporization so that there is provided a means for passing the water in form of vapor into the atmosphere and maintaining a cooler operating motor compressor unit 28.

10 While I have illustrated and described the preferred forms of my invention, I do not wish to limit myself to such details as described, but wish to avail myself of such variations and modifications as may come within the scope of the appended claim.

I claim:

15 Refrigerating apparatus comprising a cabinet having a compartment, a refrigerant evaporating element for cooling said compartment, a removable deep pan for the storage of meats and the like, slideways for slidably supporting said pan below said element, said pan also serving to collect defrost water from said element when 20 it is defrosted, an outlet adjacent the lower part of said pan for receiving and conducting said water outside said pan, and conduit means positioned in said compartment for receiving said water from said outlet when the pan is placed 25 in a certain position and including a portion for conducting said water out of said compartment, said conduit means being positioned so as not to interfere with the sliding removal of said pan.

LAWRENCE A. PHILIPP.
